United States Patent

Des. 239,534
Patented Apr. 13, 1976

239,534

ORNAMENT FOR STEMWARE OR THE LIKE

Amnon Michaeli, 135-03 73rd Terrace, Kew Gardens
Hills, Queens, New York, N.Y.

Filed Sept. 16, 1974, Ser. No. 506,408

Term of patent 14 years

Int. Cl. D11—02

U.S. Cl. D29—23 A

FIG. 1

FIG. 3

FIG. 2

FIG. 4

FIG. 1 is a top plan view of an ornament for stemware or the like, showing my new design;

FIG. 2 is a side elevational view taken from any side thereof;

FIG. 3 is a bottom plan view thereof; and

FIG. 4 is a cross-sectional view taken along the line 4—4 of FIG. 1.

I claim:

The ornamental design for an ornament for stemware or the like, substantially as shown and described.
